UNITED STATES PATENT OFFICE.

LEVIS H. DAVIS, OF WEST CHESTER, PENNSYLVANIA.

SEWING-MACHINE.

SPECIFICATION forming part of Letters Patent No. 236,788, dated January 18, 1881.

Application filed June 18, 1880. (No model.)

To all whom it may concern:

Be it known that I, LEVIS H. DAVIS, a citizen of the United States, residing at West Chester, Chester county, Pennsylvania, have 5 invented new and useful Improvements in Sewing-Machines, of which the following is a specification.

This invention relates to that class of sewing-machines in which the movement of a vibratory shuttle-lever is derived through an oscillating lever from a driving-shaft journaled in the goose-neck, and which actuates the needle-bar. Its objects are to simplify the connection between the shuttle-lever and the oscillating lever which drives it; to simplify the feed mechanism; to provide a take-up which is simple in construction and prompt to act and accommodate itself to the tension of the needle-thread; to provide a simple and reliable tension device for the needle-thread.

In the accompanying drawings, Figure 1 is a vertical longitudinal section through the center of the machine. Fig. 2 is a transverse section of the machine on line $\alpha\alpha$ of Fig. 1. Fig. 3 is a front view of the take-up devices. Fig. 4 is a bottom view of the machine. Fig. 5 is a front view of the head of the machine and bed-plate. Fig. 6 is a rear view of the front plate of the head and the lever and spring 30 which actuate the take-up, the lug of the needle-bar which moves the lever being shown in section. Fig. 7 is a detached view of the vibratory lever through which motion is communicated from the driving-shaft to the shuttle-lever, and showing, also, a section of the crank-bend of the driving-shaft and its friction-roller and the pivot-pin of the lever. Fig. 8 is a similar view of the lever through which motion is communicated to the feed-lever. Fig. 40 9 is a top view of the tension-spring. Figs. 10 and 11 are detail views of the take-up mechanism. Fig. 12 is a section on line $y\mathbf{y}$, Fig. 4. Fig. 13 is a section on the line $z\mathbf{z}$, Fig. 4. Fig. 14 is a section on line $z'\mathbf{z}'$, Fig. 4. Fig. 45 15 is a detached bottom perspective view of the feed-dog carrying-bar. Fig. 16 is a detached view of the cam which operates the lever communicating motion to the feed-lever.

The letter A indicates the driving-shaft arranged through the goose-neck B, which is cast in one piece, flaring at its front to form the head C, and having a screw-threaded open-

ing at its rear end to receive the removable bearing b. Where it opens into the head C the goose-neck has formed in its bore a bearing for the sleeve d, which projects from the center of the rotary disk D, and is removably secured upon the front end of the driving-shaft, forming the front journal thereof. In its rearward portion the driving-shaft has 55 formed a crank-bend, A', upon which is mounted a friction-roller, a, and to the rear of the bend A' there is removably secured upon the shaft a cam-roller, D', having a sleeve, d', which fits in the bearing b and forms the rear journal of 60 the shaft. The bend A', while extending laterally sufficiently to give the desired throw, is long and gradual, so that the friction-roller 65 may be freely slipped to its place from the front end of the shaft.

Near the rear end of the driving-shaft is mounted a driving-pulley, E, provided with a sheave, E', and screw-threaded sleeve e, upon which travels a nut, E'', having wings e', by which the nut may be turned to jam it against 75 a fixed shoulder, e'', on the end of the shaft, and force the pulley against the end of the bearing d', thus locking the pulley to the shaft. On releasing the pulley it may run freely and be used to operate the bobbin-winder in the 80 ordinary manner. As such devices are not claimed herein a more particular description is deemed unnecessary.

The letter F designates the oscillating lever, through which motion is transmitted from the 85 driving-shaft to the shuttle-lever G, pivoted on a pin, g', projecting downward from the bed-plate and extending forward in the usual manner. At its upper end the oscillating lever F is provided with a cam-slot, F', in which 90 plays the friction-roller a, mounted upon the bend A' of the driving-shaft. The pivot-pin f, supported in the walls of the vertical portion B' of the goose-neck, passes through a bearing, f', formed at about the middle of the 95 lever F, the lower end of which terminates in an adjustable ball, f'', which fits loosely in a circular hole or bearing, g, formed for it in the rear end of the shuttle-lever G. The lower half of the oscillating lever F consists of a 100 spring-plate, F'', which is rigid edgewise, but elastic flatwise, its office being to permit the oscillating lever F to accommodate itself to the arc of movement of the rear end of the

shuttle-lever. By this means I am enabled to dispense with the cams and slip-joints which have heretofore been used in connecting the shuttle-lever with its driver in this class of machines.

Instead of making the lower arm of the oscillating motion-transmitting lever elastic, and having its lower end passing through a hole in the feed-lever, I may make the rear portion 10 of the shuttle-lever or a hook-lever elastic, and insert its end in a hole in the lower end of the motion-transmitting lever, which may then be rigid throughout its length.

The shape of the slot F' at the upper end 15 of the lever F is such that when the driving-shaft is turned to the right and the roller has just passed upward around the elbow f³ of the slot the shuttle will have reached the farthest point in its forward movement and has drawn 20 tight the lower thread. At the same time the needle has ascended to its highest position, and thus both threads are drawn at the same time to complete the stitch. Now, as the shaft continues to revolve, the bend A' travels up 25 farther and then down to the elbow f³, throwing the shuttle back rapidly to its rearmost position. At this time the needle has descended to its lowermost position and raised sufficiently to throw a loop, and the bend of the shaft is 30 passing downward in the slot F', throwing the shuttle through the loop while the needle remains nearly stationary. Then the needle rises rapidly for a short distance and then slacks somewhat, the shuttle moving slowly as the needle ascends, and both arrive at the extreme 35 points of their movement simultaneously, their motion being reversed at the same instant, and they then operate as before.

The oscillating lever H, which drives the 40 feed-lever I, is also pivoted on the pin f, and inclines upwardly to the right, as shown in Fig. 2. It has a somewhat curved bearing-face, h, which bears against the periphery of the cam D', and its lower end has formed in it a hole, 45 h', which fits over a stud, i, projecting from the curved rear end of the feed-lever. The throw of the cam D' is arranged to cause the lever I to drive forward the feed-dog at proper intervals to feed the cloth forward in connection with the feed-raising devices, which will 50 be presently described.

Near the forward end of the lever I is a lateral projection, I', which I call the "feed-steadi- 55 er," and which, with the lever, plays in a slot formed in the flange k of the bed-plate. This steadier and its slot prevent the lever I from turning on its longitudinal axis or wabbling, and cause it to preserve a steady back-and-forth motion. The extreme forward end of 60 the lever I extends through a slot, l, formed in the end of a bar, L', which carries the feed-dog L. This bar L' is connected with an arm extending downward from the bed-plate by means of a spiral spring, l', which tends to draw the 65 bar backward and downward. The bar L' has a lip, l'', extending from its lower edge beyond

the feed-dog, the under surface of said lip being finished to form a bearing-surface, upon which, at proper intervals, presses the end of an arm, m, to raise the bar L' and feed-dogs, 70 so that the teeth of the dog will take properly into the work. The arm m projects from the forward portion of a rock-shaft, M, journaled in bearings under the bed-plate, and from the rear portion of said rock-shaft there projects 75 another arm, M', having at its end a laterally-projecting stud, on which is journaled a friction-roller, m', which bears upon the cam-face of a cross-bar, M², fixed to the rear portion of the shuttle-lever. This cam-face has an ele- 80 vated portion, m², which, as the shuttle is moved rearward and the feed-dog forward, passes under and against the roller m', pressing the arm M' upward, rocking the shaft M to throw the arm m upward also, and this arm m, striking 85 the lip l'', and thus raising the bar L' and the feed-dog, so that it will be seen that the dog is given an upward movement to catch the work, and, by the operation of the feed-lever upon the bar L', a forward motion to carry it along. 90 As the shuttle then moves forward the depressed portion of the cam-face of the cross-bar M² comes under the friction-roller m', and then the spring l' draws the bar L' and feed-dog downward and backward. 95

The feed-lever I has formed in its upper face a longitudinal groove, in which fits a swiveling fulcrum-block, n, pivoted on a pin projecting downward from a longitudinal adjustable bar, N, the upper edges of which are fitted into 100 dovetail guides formed on the bed-plate. A set-screw, N', passes down through a slot in the bed-plate, engages the rear end of the adjustable bar N, and serves to hold it at any point to which it may be adjusted. The position of the swiveling block n, of course, governs the extent of the movement of the forward end of the feed-lever. 105

From the foregoing description it will be perceived that I have produced a new four-motion feed, the various elements of which are so combined and arranged as to have a steady and certain movement easily and accurately adjusted.

In Fig. 3, which illustrates the general 115 structure of my improved take-up, I have shown the front plate of the head C in dotted lines simply to indicate the relative positions of the parts. The letter O in this figure, and also in Figs. 1 and 4, designates the needle-bar carrying the cam-grooved cross-head O', in the groove of which, indicated by dotted lines, the wrist-pin o, projecting from the face of the rotary disk D, plays to give the proper up-and-down movement to the needle-bar in 120 a well-known manner. Just below the cross-head O' there projects from the needle-bar to the right, as viewed from the front, a lug, o', from which projects forward a pin carrying a friction-roller, o². This friction-roller o², as the 125 needle-bar moves up and down, plays against the irregularly-curved or cam-shaped edge of 130

an arm, P, which is held against it by a spring, p, (shown in dotted lines in Fig. 3, and in full lines in Fig. 6,) which is a rear view of the front plate, C'. From the front face of the arm P there projects a stud, p', having a screw-hole tapped through its center, and this stud p' fits into a hole cut through the front plate and extends very slightly beyond the front face of said plate.

10 Q indicates a disk (having its edge serrated for a purpose hereinafter explained) arranged against the projecting end of the stud p', and having a central hole coinciding with the screw-hole of said stud.

15 R indicates the take-up arm having the usual hook at its lower end, and at its upper end a centrally-bored circular head, R', having formed in its rear face an annular recess, r, in which is arranged a convolute spring, S,

20 the outer end of which is secured to the head of the arm R by being passed through a hole in the same, while its inner end is similarly secured to the disk Q. A shoulder-screw, Q', is passed through the head R' of the arm R,

25 and its annular shoulder q sets against the disk Q, while its screw is driven into the central screw-hole of the stud p'. The arm P is thus held in proper position and the spring S secured in the recess r, between the head R' and

30 the disk Q, the plain-shouldered portion of the screw Q' forming a pivot, on which the arm R swings. A stud, t, projecting from the face of the front plate, limits the movement of the arm R to the right or outward.

35 The parts being in position as now described and shown, when the disk Q, by means of its serrations, is turned in the direction of the arrow, Fig. 3, the inner end of the spring S will be carried with it, the outer end of said spring

40 moving in the opposite direction and carrying the arm R against the stud t, and it is obvious that the further the disk is then turned the greater will be the tension with which the spring holds the arm R outward or against the stud t, and the disk Q, it will be seen, thus

45 serves to regulate the tension of the spring. Now, when the needle-bar is at the upper portion of its movement, as shown in Fig. 3, the curved portion P' of the edge of the arm P, and consequently the said arm is forced to the left, against the tension of its spring p, and the stud p' in turning carries the disk Q with it, moving the inner end of the spring S in the

50 direction opposite to that indicated by the arrow, and consequently decreasing the tension of said spring and the force with which it presses the arm R outward. At this point of the movement of the needle-bar it will be un-

55 derstood that the needle-thread is drawn up by the bar, and there is no slack to be taken up; hence the decreased tension of the convolute spring S permits the arm R to readily an-

60 swer the pull of the thread and move inward to assume a position ready to move outward and take up the slack of the thread when the

bar again moves downward and brings the roller o² against the edge of the extended curve P², at which point the spring p is permitted to draw the arm P to the right, and 70 turn the stud p' and disk Q to increase the tension of the spring S, so that the take-up arm R will be forced outward to take up the slack in the thread. As the needle-bar now moves farther downward, the roller o² is carried 75 out of the curve P², and against the straight edge P³, forcing the arm P again to the left, decreasing the tension of spring S as before, so that the take-up arm R readily gives up the slack thread, lessening the tension on 80 the thread so as not to interfere with the formation of the loop. As the needle-bar rises the operation of the take-up is repeated in inverse order.

The tension device proper of the needle-thread, which is arranged upon the goose-neck between the needle-bar and the spool, consists of a flat-spring-plate, T, curved downward at its rear end and supported by two flat-topped lugs, t' and t², from the front one, t', of which 90 projects upward a split stud, U, which fits loosely through a hole, t³, in the forward end of said plate T, a thread-slot, t⁴, being cut through from said hole to the end of the plate. The rear end of the plate T is tapered to a 95 point, T', which rests upon the top of the lug t², to which the plate is secured by means of a screw, V, which passes through it and into a hole tapped in the lug, the shoulder v of said screw bearing upon the upper surface of the 100 plate. On the under side of the plate T is preferably secured a thread hook or guide, t⁵. The thread is to be drawn from the spool under the plate T, through the guide t⁵, between the forward end of the plate and the top flat 105 face of the lug t', and then through the split stud U, through a thread-eye, u, on the head C, and thence through an eye, u', formed in the top of the needle-bar. It is led thence down in front of the front plate, C', as shown 110 in Fig. 4, through a guide, w, through the hook of the take-up arm, and then through the lower guide, w', to the needle. This tension device is in the main similar to one long in use, and my improvement consists in pointing the rear 115 end of the plate T, so that the plate will rock on the point and permit the entire width of the front end to press upon the face of lug t' when the plate is warped by variations of temperature or the varying strain put upon it. 120 The similar tension-springs heretofore used have had extended rear bearing-edges, and, owing to the great difficulty in forming and keeping this edge of a spring-plate precisely parallel with the front bearing-face, the spring 125 so formed is very unreliable, as is well known, for when the rear transverse edge is forced snugly against its seat one edge only of the front bearing-face is generally close upon the top face of the forward lug, so that there will 130 not be a proper pressure upon the thread.

In placing the parts of the machine together

the oscillating levers F and H are inserted through the lower opening of the goose-neck, and secured in place by the pin f, inserted from the outside. The friction-roller a is then 5 slipped upon the shaft and secured by any suitable means. In the present instance a shoulder is formed on the shaft to limit the rearward movement of the roller, and a washer, a', held by a pin, is placed in front. The shaft 10 is then inserted through the rear screw-threaded opening of the goose-neck to the left of the lever H, through the slot F' in the upper end of lever F, and its front end projected far enough in front to permit the disk D and 15 sleeve d to be placed thereon and secured in any suitable manner—as, for instance, a pin passing through the sleeve and shaft. The shaft is then drawn rearwardly to seat the sleeve d in its bearing, this sleeve forming 20 the (as will be remembered) front journal of the shaft. The cam D', with its sleeve d', is then slipped upon the rear end of the shaft, an opening in the front end of the cam fitting over a projection, d'', on the shaft, in order to 25 prevent the cam from turning independently. The removable screw-threaded bearing b is then passed over the rear end of the shaft and screwed firmly into the opening in the goose-neck, passing also over the sleeve d' and forming 30 the bearing of this sleeve, which, it will be borne in mind, forms the rear journal of the shaft.

The interior parts of the machine, it will be seen, are, by their construction and arrangement, all enabled to be properly placed and secured from the outside, and thus a great convenience effected.

I do not confine myself to any particular shape of cam at the upper end of the oscillating arm F, as a different shaped cam might be used and the driving-shaft turned in the opposite direction with the same result.

Having now described my invention, what I claim is—

- 45 1. The combination, with the needle-bar of a sewing-machine, the connected driving-shaft journaled in the goose-neck above the bed-plate and provided with a crank-bend, and a shuttle-lever fulcrumed below the bed-plate, of an intermediately-fulcrumed motion-transmitting lever having at its upper end a curved cam-slot, substantially as described, embracing the crank-bend of said driving-shaft, and having its lower end suitably connected with the shuttle-lever, the lower arm of said motion-transmitting lever being elastic in a direction at an angle with its movement of oscillation, but rigid in the direction of its said movement, essentially as set forth, where- 50 60 65 60 by a varying movement with respect to the needle is given to the shuttle, and the lower end of the motion-transmitting lever is enabled to accommodate itself to the arc of movement of the rear end of the shuttle-lever.
- 65 2. The combination, with the driving-shaft of a sewing-machine and an oscillating lever

fulcrumed under the bed-plate, of an intermediate motion-transmitting lever connected to the lever below the bed-plate, and with the driving-shaft, the said levers being constructed, 70 as specified, whereby the end of one may yield to conform to the arc of movement of the connected end of the other, substantially as described.

3. The combination, with the driving-shaft 75 of a sewing-machine, journaled in the goose-neck, and a shuttle-lever fulcrumed below the bed-plate, of an intermediately-fulcrumed oscillating lever having its opposite ends suitably connected with the driving-shaft and shuttle- 80 lever, respectively, and its lower arm elastic in a direction at an angle with its movement, but rigid in the direction of its movement, substantially as and for the purpose set forth.

4. The combination, with the driving-shaft 85 of a sewing-machine, journaled above the bed-plate, and a lever fulcrumed below the bed-plate, of the motion-transmitting oscillating lever F, having its lower arm formed of a flat-spring plate, F², provided at its lower end with 90 suitable means for its connection to the lever, and its upper end loosely connected with the driving-shaft, substantially as described.

5. In a sewing-machine, the combination, 95 with the vibrating feed-lever I and the loosely-connected bar L', carrying the feed-dog L and a suitable spring for holding said bar normally in its lowermost and rearmost positions, of the rock-shaft M, provided with the arm m, bearing against the under side of said bar, the 100 shuttle-lever and suitable intermediate devices operated thereby for rocking said rock-shaft at proper intervals, substantially as and for the purpose set forth.

6. In a sewing-machine, the combination, 105 with the vibratory feed-lever I and the loosely-connected bar L', carrying the feed-dog L, of the rock-shaft M, provided with the arm m, bearing against the under side of said bar, and the rear arm, M', extending under the bed-plate, the shuttle-lever provided with the cam-faced cross-bar m², arranged to operate upon the free end of said arm M', and a suitable spring arranged to hold the bar L' normally 110 in its rearmost and lowermost positions, sub- 115 stantially as described.

7. In a sewing-machine, the combination, 120 with suitable thread-guides, the spring-actuated curved arm P, take-up arm R, loosely pivoted to said curved arm, and the spring S, 120 having one end connected to said take-up arm, and the other end connected to the said curved arm, and the needle-bar provided with a suitable projection for operating against the edge of said curved arm, substantially as described. 125

8. The combination, with the curved arm P, having the stud p' arranged to turn in a hole in the front plate, C', of the disk Q, arranged against the front end of said stud, the take-up arm R, having its head arranged against said disk, and the spring S, having one end secured 130 to said disk and the other to the head of the

lever, and the shouldered screw Q', securing said disk to said stud and forming the pivot of said take-up arm, substantially as described.

9. The combination, with the flat-topped supporting-lugs t' t², the former or front one of which is provided with an upward-projecting split stud, U, of the flat elastic tension-plate T, having at its forward end a hole fitting loosely around the stud U, and an open slot 10 leading from said hole through the end of the

said tension-plate, substantially as and for the purpose set forth.

In testimony whereof I have hereunto set my hand in the presence of two subscribing witnesses.

LEVIS H. DAVIS.
